RELEASE AND LET-BACK MOTION.

986,006.

Specification of Letters Patent.

Patented Mar. 7, 1911.

Application filed April 8, 1908. Serial No. 425,867.

To all whom it may concern:

Be it known that I, FREDRICK HOWARD, a citizen of the United States, residing at Lowell, in the county of Middlesex and 5 State of Massachusetts, have invented certain new and useful Improvements in Release and Let-Back Motions, of which the following is a specification.

This invention relates to looms, and more 10 particularly to automatic filling replenishing looms wherein the filling in the working shuttle is replenished or changed automatically when required, my invention having for its object the production of novel means 15 for releasing and letting back the cloth take-up roll or other mechanism by which the cloth is taken up as it is woven.

In the type of loom referred to when the filling fails, or when the bobbin is changed 20 in the working shuttle, a thin place will be made in the cloth if the latter is taken up without interruption, because one or more picks contain no filling or only a partial length of filling. To avoid the formation of 25 such thin places in automatic filling replenishing looms means is provided to act, whenever the running filling breaks or runs out, and disengage the take-up pawl from the ratchet which operates the take-up mechanism, thereby arresting temporarily take-up 30 of the cloth and also permitting retrograde rotation of the ratchet a predetermined amount, usually two teeth. The tension of the warp causes the let-back of the take-up

35 mechanism, so that the two or more imperfect or empty picks in the cloth which otherwise would accompany change of filling are compensated for and obviated. Should the change of filling be improperly effected 40 after a predetermined number of picks the filling stop-motion operates to effect stoppage of the loom automatically. Provision is not always made, however, for cases in which the loom is stopped by the breaking 45 of a warp thread or otherwise. In such cases the weaver, either to repair the break or through clumsiness or ignorance, frequently moves the lay back and forth several times, thereby causing the take-up 50 mechanism to operate and resulting in the formation of thin places in the cloth.

My present invention provides means whereby, upon an automatic change of filling, take-up is arrested temporarily and the

take-up ratchet is let back two or more teeth, 55 automatically, and I have also provided means whereby, if the filling stop-motion stops the loom the take-up pawl is rendered inoperative until the break is repaired.

When the loom is stopped by the filling 60 stop-motion, or by hand, the apparatus is so constructed and arranged that the resulting movement of the shipper to stopping position will operate through the medium of the warp stop-motion rock-shaft to abnormally 65 position the take-up pawl-carrier and throw the pawl thereon out of engagement with the ratchet and such disengagement is maintained until the shipper is again thrown on or moved to running position. If the loom 70 is stopped by the warp stop-motion the turning of the rock-shaft on which the shipper knock-off arm is mounted will effect disengagement of the take-up pawl and the ratchet, and it follows that in all three cases 75 the rock-shaft of the warp stop-motion will be turned to effect abnormal positioning of the take-up pawl-carrier.

When a loom equipped with my invention is stopped it follows that the weaver can 80 move the lay back and forth as much as desired without taking up any cloth or leaving any thin places therein.

The novel features of my invention will be 85 fully described in the subjoined specification and particularly pointed out in the following claims.

Figure 1 is a side elevation of the parts of a loom directly connected with or adjacent the mechanism embodying my present invention, the warp stop-motion rock-shaft and the lay rocker-shaft being shown in section; Fig. 2 is an enlarged perspective view of the lifting finger, to be referred to; Fig. 3 is a top plan view, enlarged, of the disengaging member or arm for the take-up pawl-carrier; Fig. 4 is a detail in side elevation and part section, enlarged, showing the adjustable connection between the disengaging member and the rock-shaft of the warp 90 stop-motion. Fig. 5 is a detail view of a portion of the loom-side, the knock-off arm for the shipper, and the warp stop-motion rock-shaft on which said arm is mounted, the link which operates said rock-shaft being 95 100 105 partly shown.

In Fig. 1 A is a part of the usual frame for the cloth-roll slide of the loom, and B is

- the depending lever arm operated by or through the filling or weft-fork upon failure of the filling. Said arm B is pivoted to the frame A at 10 and is so actuated by the 5 filling-fork mechanism when a change of filling is called for, due to breakage or running out of the filling in the working shuttle, that it is moved into dotted line position, Fig. 1.
- 10 C is the take-up ratchet which, through the usual train of gears, not shown, operates the sand or take-up roll, and D is the take-up pawl-carrier, having fixedly mounted thereon the take-up pawl 20 which engages the teeth of and intermittently actuates the ratchet C. The pawl-carrier D is pivotally connected with and longitudinally reciprocated by an arm 30 carried by the lay-sword N, fulcrumed on the usual lay 15 rocker-shaft E, and as will be apparent the intermittent action of the pawl 20 will rotate the ratchet C in the direction of the arrow in Fig. 1.
- F is the usual detent pawl, held by 20 gravity in normal engagement with the ratchet C to prevent retrograde rotation thereof, said detent pawl being pivotally mounted at 41.
- G is the let-back pawl, loosely mounted on 25 the pivot 41 to coöperate with the ratchet, said pivot 41 passing through a slot 40 in the pawl G, the latter having at times a sliding movement with relation to the pivot, in practice adjusted as to its length by pins, 30 not shown, to determine the number of teeth the ratchet C can turn back when released from the control of the take-up and detent pawls, in a manner familiar to those skilled in the art. When the pawls 20 and F are 35 disengaged from the ratchet the latter lets back the cloth a distance determined by the effective length of the slot 40.
- At the lower end of the lever arm B I 40 preferably provide a slot 11, and by a suitable bolt and nut 12 I secure to said arm the lifting finger H, shown separately in Fig. 2. The finger H is also slotted at 13, so that by such slot and the slot 11 the finger may be 45 adjusted longitudinally and vertically. At 50 its rear end the finger has a lateral projection or nose 14 which extends under the detent pawl F, whereby, upon filling failure and the movement of lever arm B to dotted line position, Fig. 1, the change in the position of the lifting finger will lift the pawl F 55 from engagement with the teeth of the ratchet C. This finger H is so shaped and adjusted that under normal conditions it is 60 in contact with or very close to and under 65 the upper end 21 of the take-up pawl-carrier D, so that when the finger H disengages the detent pawl F from the ratchet it will swing back said pawl-carrier D and disengage the take-up pawl 20 from the ratchet, transfer- 70 ring control of the latter to the let-back

pawl G. Should the part 21 of the pawl-carrier D be too far away from the lifting finger H to be moved thereby as described the detent pawl F when raised will strike the under part of the pawl-carrier D and 70 throw the pawl 20 out of action.

In the present embodiment of my invention I have provided the warp stop-motion rock-shaft K with a collar 50 having at the top a slot or groove 53, see Fig. 4, adapted 75 to form a seat for a disengaging member or arm L provided with a slot 54 for the reception of a set-screw 51, by means of which arrangement the member L is attached adjustably to the collar 50. The shaft K corresponds in practice to the shaft g^x in United States Patent No. 729,644 granted June 2, 1903, to Northrop. As shown in Fig. 4, the set-screw 51 is tapped into the collar and bears against the shaft K, thereby adjustably 80 85 attaching the collar 50 to said shaft. A check nut 52 on the screw 51 bears upon the member L and holds it in adjusted position on the collar within the limits of the slot 54.

The rock-shaft K is mounted on the lower 90 part of the loom frame, Fig. 5, and the upturned knock-off arm M which releases the shipper upon the occurrence of a warp fault is fixedly attached to the rock-shaft, a 95 depending arm g^3 fast on the latter being pivotally connected with a link g^2 forming a part of the warp stop-motion, as in the Northrop patent, or as in Patent No. 673,825 dated May 7, 1901. When a warp fault occurs the link g^2 pulls on the arm g^3 and turns the rock-shaft K to swing the knock-off arm M forward and effect release of the shipper S. Conversely, shipper release by hand or by the filling stop-motion acts through the knock-off arm M to turn the 100 rock-shaft K in the same direction, just as if the warp stop-motion had operated. Consequently, whenever the loom is stopped, by 105 manual movement of the shipper S, or automatically by either the filling or the warp 110 stop-motion, the movement of the shipper to stopping position is accompanied by turning of the rock-shaft K and thereby the disengaging member L is raised to dotted line 115 position, Fig. 1.

Inasmuch as the free end of the member L is adjusted to be almost in contact with the take-up pawl-carrier D under normal conditions the upward swing of said member L pushes back the pawl-carrier into dotted line position, Fig. 1, and disengages the pawl 20 from the ratchet C, arresting take-up.

Preferably the take-up pawl-carrier D is 120 bent or concaved at 22 to be more readily acted upon by the disengaging member L, and while I prefer to connect the latter with the warp stop-motion shaft K it can in practice be connected with any other convenient shaft which has a definite rotative move- 130

ment accompanying movement of the shipper to stopping position.

In some prior structures the detent pawl has been disengaged from the ratchet by the 5 movement of the take-up pawl-carrier to render the take-up pawl inoperative, such movement of the take-up pawl-carrier being effected by engagement with an arm operated similarly to the lever arm B herein, 10 upon breakage of filling or change of filling, thus permitting the ratchet to let back a distance governed by the let-back pawl. Should the disengaging member L of my invention be applied to such a construction it 15 will be apparent that whenever the loom was stopped by hand or by the warp stop-motion the inoperative positioning of the take-up pawl-carrier would also release the ratchet from the control of the detent pawl, 20 permitting let back of the cloth. This is not desirable, for in such a case no picks have been lost. By my invention, however, picks whenever lost are compensated for by the let back motion, but when no picks are lost such 25 let back device does not operate. So, too, when the loom is stopped by either the filling or the warp stop-motions, or by hand through the medium of the shipper, the take-up mechanism is thrown out of action and 30 hence the lay can be moved back and forth freely without injuring the evenness of the cloth.

Having fully described my invention, what I claim as new and desire to secure by 35 Letters Patent is:—

1. In a loom, a take-up ratchet, detent and let-back pawls coöoperating therewith, and a take-up pawl-carrier having an actuating pawl fixedly mounted thereon and in engagement with the ratchet, combined with an arm adapted to be operated by or through a 40

change in the running filling, a lifting finger fixedly attached to said arm and passing under the take-up pawl-carrier and the detent pawl, to throw them out of action, a warp 45 stop-motion shaft, and a disengaging member attached to the warp stop-motion shaft adapted to temporarily engage and bodily move the take-up pawl-carrier away from the ratchet to thereby disengage the actuating pawl from the ratchet when the loom is 50 stopped.

2. In a loom, a take-up ratchet, an actuating pawl and detent and let-back pawls normally in engagement with the ratchet, and a 55 take-up pawl-carrier on which said actuating pawl is fixedly mounted, combined with means operative upon a change in the condition of the running filling to coöperate directly with said detent pawl and also with the take-up pawl-carrier and release the ratchet from control thereby, whereby take up of the cloth is arrested and the let-back pawl coöperates with the ratchet to permit let back, and separate means operated by or 60 through stoppage of the loom to act directly and temporarily upon and move the take-up pawl-carrier and disengage its pawl from the ratchet while the latter remains under the control of the detent pawl, said separate 65 means including a shaft rocked whenever the loom is stopped, and an arm fast on said shaft and moved by turning thereof into direct engagement with and to move the pawl-carrier away from the ratchet. 70

In testimony whereof I affix my signature in presence of two witnesses.

FREDRICK HOWARD.
